METHOD AND MEANS FOR SECURING
UPHOLSTERY MATERIAL

Benjamin F. Monroe, Chicago, Ill., assignor to
Tropic-Aire, Incorporated, Chicago, Ill., a corporation of Delaware

Application July 24, 1940, Serial No. 347,141

12 Claims. (Cl. 155—184)

This invention relates to improvements in the upholstering art and has for its main object to provide method and means by which covering material can be easily applied by unskilled persons and held in position without the use of nails, tacks, screws or glue.

Heretofore it has been necessary to employ skilled persons for applying finishing or equivalent covering material for upholstering and similar purposes, and it has been necessary to use tacks, nails, or glue to secure the material. Moreover, when the material became dirty it either had to be cleaned in situ, or had to be removed, cleaned and reapplied by skilled persons.

The upholstery material used for bus seats is subject to much wear and tear, and soon becomes soiled or unsightly so that frequent cleaning and/or replacement is necessary. The present invention particularly provides means by which the upholstery material of bus seats can be quickly applied or removed from any part of the seat by unskilled persons, and provides a tackless, nailless and glueless construction and method.

The same piece of upholstery can be easily taken off and reapplied any number of times as is needed, for example, for cleaning or repair, and the invention is equally applicable to wood or metal frames or bases.

Moreover, the device provides for a clean, neat, uniform upholstery line by permitting easy smoothing out and pulling taut of the variety of materials used in this art, such as leather, mo-hair, various cloths and flexible fabrics. By the use of this invention material is as easily attached to or detached from a metal base or frame as to or from wood.

Features include: the frictional lock principle between cloth and wood or metal; the frictional lock as exemplified in shoulder locking; the combination of friction and shoulder locking; the wrapping of the material about a frame member followed by frictional locking; and all details of construction shown; along with all broader ideas of means disclosed in this application.

Features, objects and advantages of the invention are disclosed in the description of the drawing, and in said drawing—

Figure 1 is a side elevation partly in vertical section showing the invention applied to the back of a seat;

Figure 2 is a plan section on line 2—2 of Figure 1;

Figure 3 is a detail section illustrating a second application of the invention;

Figure 4 is a detail section illustrating a third application of the invention.

In the drawing the numeral 1 generally indicates the base of a seat which is mounted on a suitable pedestal 2. This may be a bus seat. Rising from the base of the seat at the rear thereof are hollow extensions 3, only one of which is shown. Secured in the hollow extension are the lower ends of an arched back frame generally indicated at 4. The frame is herein composed of a single suitably formed tubular length. The tubular formation is attained in part by the use of a channel element 5 (see Figure 2). This channel member 5 is herein converted into a tube by the use of a cross member 6 having flanges 7, 8 extending in opposite directions as shown and secured to member 5. The back 4 does not have to be of metal. It may be of a solid piece of wood.

Element 8 cooperates with the terminal portion 9 of the longer inner side of the channel to provide a forward projection or extension, that is, an extension forwardly of the front surface 10 of the cross-piece 6. There is no intention, of course, to be entirely limited to the particular construction of the back. The main feature is the provision of any suitable projection as part of a friction-holding system or structure for the purpose herein. It will be understood that the frame or base may be of wood or any other suitable material and it will be further understood that the invention can be applied to many structures other than to the back of a chair. Nevertheless, the invention is specifically claimed in relation to a chair back. The supports which are bridged by the upholstery material have been generally designated 13. The invention is applicable generally for the attachment of material to various structures without the use of any fastening devices except that involving the friction and/or abutment principles herein shown.

In the embodiment of the invention as shown in Figures 1 and 2 a hanging back cloth 12 bridges the projections formed by the elements 8 and 9, and this hanging back cloth is secured at three margins to the front face 10 of the element 6 by means of a suitable fastening device 14, such as a suitable screw, passing through a channel member 15. The projections or extensions formed by the elements 8 and 9, and designated by the numeral 29, extend the full length of the back marginally entirely therearound. The mar-

ginal location is preferred, although the invention is not entirely limited thereto.

On the forward side of the back cloth is placed a seat back filler material generally indicated at 20. This material may be of any suitable kind such as paratex and may be reenforced at the ends by yieldable rubber 21. Paratex is a combination of curled hair treated with latex and is well known in this art. In some instances the padding or filler may be omitted. The back cloth is secured at the bottom to the base 1 by being suitably attached to a cross bar 16'. This bar is U-shaped in cross-section, and the end of the back cloth is clamped within it.

The invention herein is applied to the attachment of the finishing or facing material and in this instance the material may comprise a front section of mohair 22 suitably attached as at 23 to a leather strip indicated at 24. The leather is passed rearwardly and around the member 13 and is then brought forwardly. Thus the leather is caused to snugly embrace the member 13. The end of this leather is rolled to form a bead 16 and may then be suitably stitched. This bead may be formed in any suitable manner and is intended to provide a marginal enlargement or thickening of the material to provide an abutment. The end or marginal portion of the leather piece 24 is then forced in between the projection 29 formed by the elements 8 and 9, and the rear surface of the back cloth 12. It will be noted that a shoulder 11 is formed at the inner side of the projection 29, and that in this embodiment of the invention a space 18 is provided between the back cloth 12 and the surface 10 to receive the bead. The projection thus serves to form a shoulder and a friction surface.

In all cases the material is preferably wrapped about the member 13 or its equivalent before being forced or tucked in as above described. It has been found that the herein disclosed scheme of connection is a very secure connection and that compression of the padding and consequent loosening of the covering material or upholstery does not correspondingly loosen the connection, but that the material continues to be strongly frictionally held around the projections and between them and the taut elastic or inelastic, but preferably flexible webbing 12.

It will, of course, be understood that in using the word "elastic" I do not necessarily mean made of rubber. The ordinary backing webbing used in the upholstering trade will serve. It is only necessary that the material have sufficient "give" to allow tucking to occur, and thereafter be under tension to keep the material against the projection. Inasmuch as friction is depended upon to secure the parts, a rough surfaced upholstery material will increase the frictional effect on the tucked in portion. For the backs of bus seats and in general this webbing should be of pleasing texture and appearance.

When I use the expression "held solely by friction in part provided by said projection," I mean to include friction action either between the projection and the material itself as in Figure 3, or between the projection and a second material as shown in Figure 2, the latter figure disclosing the preferred use in conjunction with the back or other suitable part of a piece of furniture. When I use the words "back cloth" I mean a material in addition to the cloth or fabric or textile finishing material, that is, any material suitable for the purpose.

Moreover, I do not intend to be limited to the

use of a single layer of the material but intend to cover the tucking in of plural layers or thicknesses, and to cover the use wherein there is first the tucking in of one material and then the tucking in of a second material thereover. Thus, where it is desired to use washable covering material as for summer travel for bus seats, such material can be laid over the original upholstery material and can be easily attached and as easily removed for washing and can again be easily attached after washing. It is to be noted that both in the application of the original upholstery material and in the application of any additional or supplemental covering material, such applications can be made by unskilled persons, and this is a very important feature.

Although I have used the expression "rectangular projection," I do not intend to be entirely limited to the particular cross-sectional shape shown, because it may be rectangular or of other configuration. The broader aspect of the invention is the tucking in between a projection and sheet material to obtain a friction lock. An important phase of the invention is the use of a shoulder and a marginal enlargement in addition to the friction action. The fabric is taut so that the terminal portion of the material is frictionally held against accidental displacement and without the use of other fastening devices of any kind, such as nails, screws or glue.

While the rectangular configuration of the projection is preferred and is of considerable advantage in providing corners for increasing the frictional retaining action on the material, it is not absolutely essential that the projection provide corners, because when the material is stretched tightly or tautly across the projection and then the terminal part of the material is passed around the frame member and is forcibly tucked in between the projection and the material as shown, a frictional lock is obtained. It will, of course, be understood that friction is increased by rectangular configuration and that this is the preferred construction and that, moreover, such a construction provides a more marked shoulder to cooperate with the enlarged or thickened margin of the material. As has been explained before, in cases where a welt is used, the welt lies inwardly of and in opposition to and against the shoulder, or the material is packed in the space 18, or its equivalent.

The application of the invention shown in Figure 3 differs only from that shown in Figure 2 in that no back cloth is used, but the covering or finishing material 28 itself bridges the projections 29, only one of which projections is shown in this figure. In this instance the use involves only a single length of finishing material 28 which is brought around the member 13 and is tucked between the projection 29 and a portion of the same length of material. The numeral 29 has been used to indicate that the projection may be of any suitable kind, and is not necessarily formed of the members 8 and 9 as in the application of the invention shown in Figure 2. As before stated, there is no intention to be limited to the manner in which the projection is formed. It may be formed in any suitable manner and have any suitable shape and may be formed on any suitable base material, not necessarily a hollow base or one made of metal.

Figure 4 illustrates an application of the invention for connecting a protecting cover material such as a washable seat covering material for summer use, and illustrates how the invention

can be used for easily applying and securing such material over the ordinary upholstery finishing material. In this case the back cloth 12 may be used as in Figure 2, and the same is suitably connected. The finishing material is indicated at 34 and is brought around the element 13 and tucked in between the projection 29 and the back-cloth material 12. At any time later a wash material indicated at 35 may be applied over the material 34 and this is brought around in the same manner as the material 34 and tucked in between the already tucked in material 34 and the back-cloth material 12 as shown. The beads are shown and are preferred on both materials and are respectively indicated by numerals 16 and 36. Bead 36 may be omitted for the wash material, although the use of the bead herein represents a preferred form of the invention. It will be understood, however, that broadly the invention involves the holding by abutment and/or friction scheme, that is, the tucking in of the cover material under tension of the back cloth or equivalent element and a projection, or the tucking in of the cover material against itself and the projection, as shown in Figure 3.

When I say that material lies in opposition to the projection and embraces the member and is forcibly frictionally held between the projection and flexible material, I mean to cover generically the tucking and friction holding scheme, whether the tucked material engages itself as in Figure 3, or engages a second material as in Figures 2 and 4.

The finishing material 22 is secured by tucking it in on three margins of the back frame 4. To the lower end 31 of the finishing material 22 is attached a piece of rubber or other suitable friction material 38, and these portions 31 and 38 are brought behind the paratex layer 20 and held as shown in Figure 1.

This construction has only been shown in Figures 1 and 2. Although there is no intention, of course, to limit the invention entirely thereto, this holding scheme is also claimed alone and in combination with the tucking in scheme previously described. In this instance the end 31 is held at the bottom partly by means of its own friction and partly by the frictional action of material 38, with the back cloth 12 and paratex 20, or equivalent friction materials. In this case again there is a frictional holding function, this time between two fabrics 20 and 12 whose surfaces frictionally cooperate with the finishing material 22 and its extension 38 for anchoring the bottom of the cloth 22.

It will be understood that although this invention has been shown applied to the back of a seat, it is applicable as well to a seat cushion of a seat and is applicable to any device to which upholstering finish can be applied, whether padding is used or not. The broad conception of the invention is the frictional and/or abutment lock of the upholstery without the use of nails, screws or glue.

What I claim is:

1. A member having a projection extending therefrom, material stretched and lying in opposition to said projection and surrounding and embracing said member and having an end forcibly frictionally held between said projection and flexible stretched material, connected to said member.

2. A member having an elongated projection extending therefrom, material stretched and lying in opposition to said projection and surrounding and closely embracing said member and having a terminal portion frictionally held between

said projection and flexible stretched material connected to said member, said projection providing a shoulder at its inner side, and said material having a terminal bead which lies at the inner side of said shoulder.

3. In combination with a pair of spaced members, a flexible base material connected in taut bridging relation to said members, each of said members having an elongated marginal extension at its inner side and opposed to the base material, cushion material on said base material and finishing material covering said cushioning material and having opposite ends embracing the said members and each forced between said base material and a corresponding extension, to occupy a position at the inner side of said extension, each end of said finishing material being thickened.

4. A chair comprising an arched structure providing spaced members, a flexible webbing bridging and suitably connected in taut bridging relation with said members, cushioning material on said webbing, each of said members having a marginal longitudinal projection opposed to the webbing, and a single piece of material covering said cushioning material and surrounding said members and having its margins forced between the webbing and corresponding projections and with said margin portions disposed at the inner side of the corresponding projection.

5. A seat back providing two spaced members, each having at its inner margin a longitudinally extending projection providing a forwardly facing shoulder, a cloth stretched across said projections and secured to said members at points outwardly from the projections, padding material arranged upon the cloth, and finishing material covering the padding and stretched tautly thereagainst to press said padding against the cloth and closely embracing said members and having opposite terminal portions respectively forced to positions between the corresponding projections and said cloth against said shoulders, and so forced against the action of the stretched cloth and held by friction.

6. In combination with a pair of spaced members, a base material connected in taut bridging relation to said members and having a resilient and compressible cushioning material thereon, each of said members having an extension opposed to the base material, a finishing material arranged against the cushioning material and having opposite end portions embracing said members and forced between the base material and corresponding extensions, said finishing material being drawn tautly over said cushioning material to hold it compressibly confined.

7. In combination with a support, a flexible base material secured thereto, a padding overlying the base material, a finishing material overlying the padding and secured to the support and having an end brought around an edge of the padding and disposed between the padding and the base material, said finishing material having a second material secured thereto which also cooperates with the base material and with the padding material to frictionally secure the end of the finishing material.

8. A chair comprising a seat, an arched back structure for said seat having generally the form of an inverted U, a webbing in taut bridging relation with said arched structure, and cushioning material on said webbing, said arched structure having a marginal projection opposed to the webbing and a single piece of material

covering said cushioning material and having portions wrapped around portions of the arched member and having its marginal portions forced and held by friction between the webbing and said projection.

9. A chair comprising a seat, an arched back for said seat having generally the form of an inverted U, a webbing in taut bridging relation with said arched structure and having a portion connected to the seat, cushioning material on said webbing, said arch having a projection opposed to the webbing and a single piece of material covering said cushioning material and having portions wrapped around portions of the arched member and having its marginal portion forced and held by friction between the webbing and said projection, the bottom part of said covering material being tucked between said cushioning material and webbing and frictionally held therebetween.

10. A chair comprising a seat and a back for the seat comprising a frame, a webbing in taut bridging relation with said frame on three sides, and having a fourth side connected to the chair seat, cushioning material on said webbing, said frame having projections opposed to the webbing, and a single piece of material covering said cushioning material and having portions wrapped around portions of the frame and having mar-

ginal portions forced between the webbing and said projections, the fourth side of said covering material having attached thereto a friction material and the bottom portion of said covering material and said friction material being tucked and frictionally held between said cushioning material and said webbing.

11. A seat having a back composed of an arched frame providing two legs, a back cloth bridging and secured to the legs, cushioning material on the back cloth, finishing material laid upon the cushioning material and having portions brought outwardly and around and then rearwardly and to the inner sides of said legs and tucked between said legs and said back cloth, said legs having projections engaged by said finishing material, as so tucked.

12. A seat having a back composed of an arched frame providing two legs, a back cloth bridging and secured to the legs, cushioning material on the back cloth, finishing material laid upon the cushioning material and having portions brought outwardly and around and then rearwardly and to the inner sides of said legs and tucked between said legs and said back cloth, said legs each having a continuous projection extending lengthwise thereof and engaged by said finishing material, as so tucked.

BENJAMIN F. MONROE.
